UNITED STATES PATENT OFFICE.

CHARLES W. SPONSEL, OF HARTFORD, CONNECTICUT.

DESIGN FOR A NOZZLE FOR HARDENING APPARATUS.

SPECIFICATION forming part of Design No. 30,346, dated March 14, 1899.

Application filed February 15, 1899. Serial No. 705,584. Term of patent 14 years.

To all whom it may concern:

Be it known that I, CHARLES W. SPONSEL, a citizen of the United States of America, and a resident of Hartford, in the county of Hartford and State of Connecticut, have invented and produced a new and original Design for a Nozzle for Hardening Apparatus, of which the following is a specification.

This invention is a new and original design for a nozzle for hardening apparatus through which water or other liquid is delivered under pressure and properly directed against the object to be hardened.

Figure 1 is a plan view of my nozzle design, one of the branch pipes being shown in section taken on the line 1 1 of Fig. 2. Fig. 2 is a front view projected from Fig. 1. Fig. 3 is a side view in section taken on the line 3 3 of Fig. 1. Fig. 4 is an underneath view in section taken on the line 4 4 of Fig. 2.

This design comprises a hollow distributing-head 10, having a series of hollow branch pipes 11, extending therefrom and encompassing a substantially rectangular space. The

head is also substantially in the form of a hollow rectangle, having an external opening 13, which communicates with the interior chamber 12 of the distributing-head. The inner faces of these branch pipes are each provided with an opening 14, communicating with the hollow interior of the pipe, which in turn communicates with the chamber 12 of the distributing-head.

The leading essential feature of my design is the substantially rectangular hollow distributing-head having a series of hollow branch pipes extending therefrom, provided with inwardly-facing openings and encompassing a substantially rectangular space.

I claim—

The design for a nozzle for a hardening apparatus herein shown and described.

Signed by me, at Hartford, Connecticut, this 10th day of February, 1899.

CHARLES W. SPONSEL.
